LID FASTENER FOR SHIPPING CONTAINERS

Barkley B. Wilson, Portland, Oreg.

Application April 15, 1935, Serial No. 16,391

6 Claims. (Cl. 217—56)

This invention relates to lids or closures for containers, and to improved means for fastening such lids or closures to its associate container. The essential object of the invention resides in an improved lid and means for readily and detachably securing such lid to a closure. While not limited to any particular type of container the present invention is eminently suited for egg crates, butter and cheese boxes, onion crates, 10 and similar types of containers which are repeatedly shipped back and forth between manufacturer or producer and consumer. This for the reason that the cover may be easily attached or detached, the manner of its attachment being such that it does not harm the shipping container for the reason that nails, screws, staples and the like are not employed for securing the cover to the container. And for the added reason that the construction of the cover is such that it adequately protects the container and its 20 contents, and for the further reason that the cover may be utilized on similar containers, thus making container and covers interchangeable.

An object of the invention is to make the covers of light though strong materials. These covers in addition to their inherent strength are further strengthened by improved strengthening and bracing members which prolong the lives of such covers and provide an added protective means 30 for the containers or the products in such containers to which they are applied.

An object of the invention resides in improvements in means for fastening the covers to the containers. In the present instance a fastening member is employed which securely fastens such covers, their operation requiring little more than the placing of the covers on such containers. Furthermore the fastening means permit a ready removal of the covers from the containers, their 40 removal being instantaneous as is their placement. Added to this is the fact that no material change, and in many instances none at all, is required in containers to adapt them to the present invention.

A further object of the invention resides in the manner for attaching the fastening means to the covers. These fastening members are either permanently secured to the covers or detachably secured thereto. In both instances should the 50 cover become worn they may be detached and placed upon new covers, or should they become worn, they may be replaced by new fastening means.

These and incidental objects of the invention will become apparent upon reading the descrip-

tion thereof following, aided by the several views in the drawing, wherein—

Figure 1 is a plan view of the improved cover and attaching means. This view also discloses the bracing and strengthening means employed 5 on the cover.

Figure 2 is an end elevation of a box or crate resting upon one side. The invention is employed thereon.

Figure 3 is a side elevation of a box and shows 10 the application of the invention thereto.

Figure 4 is a fragmentary detail sectional view, enlarged. This view is indicated by the section lines 4—4 in Figure 1.

Figure 5 is an enlarged sectional detail of one 15 end of a box. This view also shows in side elevation and partial section fastening means employed in the present invention, also the means for detachably securing such fastening means to the cover of a box.

Figure 6 is a view similar to the preceding figure. This view shows a modification in the means for securing the fastening means to the box cover.

Figure 7 is a fragmentary plan view of a box cover. This is a plan of the construction shown 25 in Figure 5. This view shows the construction on the underside of the cover in outline.

Figure 8 is an end sectional detail of the construction shown in Figure 6 and is taken on the section line 8—8, looking in the direction the arrows point.

Figures 9 and 10 are fragmentary side sections and end views of box and cover and show a still further modification of the invention.

In the drawing 1 indicates a container, box or 35 crate such as an egg crate. This crate is furnished at each end with cross members 2 and 3 respectively at the top and bottom thereof. In crates of this type it is usual to employ two or more thin boards as covers. These are usually 40 secured in place by nails driven into the cross members 2. In the removal of the cover boards, the nails have to be pulled, often destroying the end braces as well as the ends of the cover boards, requiring both repairs to the end members and 45 new cover boards if the crate is to be put into further use. The aim of the present invention is to avoid this destructive practice. This is accomplished by providing improvements in the covers as well as in the fastening means for securing such covers to the crates.

In carrying out this invention it is proposed to employ what may be termed one-piece covers, that is to say, instead of employing two or more boards, to employ one board, or one mem- 55

ber of sufficient size to cover the opening to the crate. In view of added strength, and relative freedom from splintering and breaking, what is known as plywood or veneer is preferably employed. Such a cover is indicated by the numeral 4, extends from end to end of the crate, including members 2 therein, and from side to side. In conjunction with the cover there is employed certain bracing, strengthening and protecting members 5. These are preferably arcuate in cross section as shown in Figure 4, and are provided with a central groove 6 in their convex face. These braces are preferably arranged as shown in Figure 1, with one positioned transversely midway the ends of the top, and the remaining four directed diagonally from the corners toward the center of the top. These braces are secured in place by suitable fastening means such as the nails 7. They, the braces or straps 5, serve to strengthen the cover 4, protect it to a great extent from rough usage occasioned by placing articles upon the cover, and where it is desirable to stack boxes one upon another provide a smooth surface for sliding a box upon the cover 4.

In connection with the cover 4 there is employed for detachably fastening the covers to the boxes or crates, certain improvements in fasteners which form and constitute a part of the covers, so that the covers may be readily attached to any of a particular type of crate. It is the purpose of these fasteners to construct them in a manner that the tops or covers may be placed upon and secured to the container in an instant without the need of tools and as speedily removed from the containers. It is also the purpose to construct them so that when the covers are placed upon the containers they will not come off of their own accord.

These fasteners are generally indicated in the drawing by the numeral 8, and consist of horizontal portion 9 generally resting upon the cover 4, a down turned portion 10, a reversely bent portion 11 at an upward inclination, and a down turned end portion 12 which may have a slight inclination when it is understood that this portion serves as a cam member. The bending of the portions 11 and 12 provide at the angle of their union a nose, clasp, catch or ear 13 which rides upon the underside of the cross member 2 when the cover is in place. The ear 13 grips the under side of the cross member and secures and holds the cover 4 in place as will be readily understood upon examination of Figures 5, 7, and 9.

The members are made of material having a suitable amount of springiness to function as will presently appear, for which purpose flat metal strips are eminently suitable.

It is preferable to have the members 8 attached to the cover 4 in a manner that they may be readily removed or exchanged. The reason for this is that they may become bent or broken then it is desirable to replace them, or the covers 4 may become damaged and it may be found advisable to preserve the catch members by removing them from the cover. For this purpose three preferred means for attaching the catches are shown in the drawing. That shown in Figures 5 and 7 consists in providing an offset in the portion 9. An aperture 15 is provided in the top in which the end portion 16 is seated with the offset in the aperture, the portion 9 upon the upper face of the cover and the portion 16 upon the lower face of the cover. In connection therewith there is employed a button 17 pivotally mounted to the pin or rivet 18.

As will be readily understood upon examining Figure 5, one end of the button presses upon the under side of the portion 16 and secures it in place. In order to hold the button in place upon portion 16, the latter is provided with a blister 19 which is received in the recess 20 of the button. Turning the button to the point where it and the portion are disengaged releases the catch 8 which may be removed from the cover 4.

In Figures 6 and 8 is shown another means for attaching the fastening member to the cover. In this construction the portion 9 is provided with an aperture 21 proximate its end. In conjunction with portion 9 there is provided a channel 15 or socket member 22 held in place upon the cover by fastening means 23. The portion 9 enters the socket member 22. Member 22 has an aperture 24 coinciding with the aperture 21. A spring member 25 is secured to the cover by the fastening means 26 passing through it at one end, its other end bears upon the socket member 22 and is provided with a pressed out stud on the underside which enters the apertures 21 and 24 securing the member 8 upon the cover. To remove member 8 all that is necessary to be done is to raise the free end of the spring 25 until the stud has been removed from the aperture 21 after which the member 8 may be withdrawn.

A still further embodiment of the means for fastening member 8 to the cover is shown in Figures 9 and 10. In this embodiment the portion 9 has a backwardly curved end to provide a hook-like portion 28 which is hooked into the staple 29 secured in the body of the cover 4. By swinging the member 8 about it may be unhooked from the staple and removed.

In order to prevent the cover 4 slipping sideways from the top of crate 1, the underside of the cover at its ends is provided with elongated metallic strips 30 secured thereto by any suitable means. Strips 30 have a number of pressed out teeth 31 made by breaking or pressing out the material of which it is composed. These teeth bite into the juxtaposed surface of the box 45 upon which the strips rest preventing lateral movement of the cover. As an added precaution strips 30 may be provided with downturned ends 32 which extend over the edges of the container and ensure against lateral displacement of the cover.

In applying the invention to practice, it is anticipated that the spring of the members 8 will allow them to be sprung sufficiently so that the portions 12 and 13 will clear the end edge of the box and the members 2 when the cover is being placed upon or removed from the box, it being understood that members 8 are manually sprung for this purpose. In this connection the portion 12 is employed as a cam traveling over the edge 60 of the box end and brace 2. When the member 8 has its portion 13 at the lower edge of member 2 the spring of member presses the portion toward the box end to a position to securely hold against the underside of the cross member.

The covers may be removed from the crates or containers by springing out the members 8 until the portions 13 are clear of the cross members 2.

The embodiment shown in Figures 9 and 10 is caused to engage and disengage the cross members 2 by rocking such members upon the staple 29 as is readily apparent.

While a specific form of the improvement has been described and illustrated herein, it is de-

sired to be understood that the same may be varied, within the scope of the appended claims, without departing from the spirit of the invention.

5 Having described my invention, I claim—

1. In a lid and its fastener for containers, a body suitable for closing the opening to a container, fastening means for fastening the body to the container, said fastening means being positioned at the end of the body and each embodying a horizontal portion, a down turned portion at the end of the container, and an angularly bent portion terminating the downturned portion adapted to engage the under surface of a cross member at the end of the container, the horizontal portion having an offset, the body having an aperture within which the offset portion is positioned with a portion of the horizontal portion on the upper face of the body and a portion on the lower face of the body, and means for removably engaging the portion on the lower face of the body and holding it substantially against movement.
2. In a lid and its fastener for containers, a body suitable for closing the opening to a container, fastening means for fastening the body to the container, said fastening means being positioned at the end of the body and each embodying a horizontal portion, a down turned portion extending over the end of the container, and a portion terminating the down turned portion adapted to engage the underside of a cross member at the end of the container, the horizontal portion having an offset, the body having an aperture within which the offset resides with a section of the horizontal portion above and a section below the body, and a button pivotally

mounted to the underside of the body engageable with the section on the underside of the body for the purpose of holding the fastening means to the body.

3. In a lid and its fastener for containers, a closure body and means for fastening the closure to the container embodying a member having a downturned portion constituting a catch for engaging a cross member provided therefor on the walls of the container, a closure engaging portion for securing the member to the closure including a socket arranged in conjunction with the closure within which seats a section of the second portion and means for releasably securing such section in the socket. 15

4. A lid fastener for containers, a lid, a fastening device for fastening the lid to the container, said fastening device having a portion arranged with a section upon the upper surface of the lid, a section projecting through the lid and a section upon the underside of the lid; and a disengageable fastening element securing the last section upon the underside of the lid. 20

5. In lids and containers, means for preventing lateral movement of the lids relative to the containers comprising elongated metal strips secured at each end to the underside of the lid and each having punched out portions providing teeth which bite into juxtaposed surfaces of the container. 30

6. In lids and containers, means for preventing lateral movement of the lids relative to the containers comprising elongated metal strips secured at each end to the underside of the lid and each having teeth which bite into juxtaposed surfaces of the container. 35

BARKLEY B. WILSON.
